CLAIM

The ornamental design for a camera system, as shown and described.

DESCRIPTION

FIG. 1 is a front perspective view of a camera system in accordance with the present invention.

FIG. 2 is a back perspective view of the camera system in FIG. 1.

FIG. 3 is a front view of the camera system in FIG. 1.

FIG. 4 is a back view of the camera system in FIG. 1.

FIG. 5 is a left view of the camera system in FIG. 1.

FIG. 6 is a right view of the camera system in FIG. 1.

FIG. 7 is a bottom view of the camera system in FIG. 1; and,

FIG. 8 is a top view of the camera system in FIG. 1.

The broken lines depict portions of the camera system in which the design is embodied that form no part of the claimed design.
